BUILDING AND PICTURE PROJECTION DEVICE

Kenneth L. Bower, Norfolk, Va.

Application May 18, 1948, Serial No. 27,643

1 Claim. (Cl. 20—1.12)

1

This invention relates to a decorating apparatus for the interior and exterior of a building.

An object of the invention is the provision of a place of amusement in which those portions of the walls of the building above the heads of the guests are formed of translucent materials, a projection machine being disposed in operative relation with each translucent wall for projecting a picture on said wall so that the picture will be not only visible from the exterior of the building but will also be visible to the guests, the picture depicting a scene or successive scenes being illustrative of the subject matter of music being played in the building.

Another object of the invention is the provision of a place of amusement in which the upper portions of the side walls of a building are formed of translucent glass, plastic or cloth so that when a picture is projected on each of the walls, said scenic walls will be visible to the guests as decorations and visible to exterior as an attraction. The scenic effects being accomplished by the use of a projection apparatus employing stills or motion pictures for each translucent wall, the scenes depicted being illustrative of the subject matter of the music produced by an orchestra. The walls forming the screens and the projection apparatuses located above the heads of the guests, the apparatuses being disposed within or without the building, the translucent walls displaying advertising matter if desired, when the building is not employed for entertainment.

The invention is best understood from a consideration of the following detailed description in connection with the accompanying drawings forming part of the specification, nevertheless, it is to be understood that the invention is not confined to the disclosure but is susceptible to such changes and modifications as shall define no material departure from the salient features of the invention as expressed in the appended claim.

In the drawings:

Figure 1 is a view in elevation of my decorated amusement building showing means for decorating temporarily the interior and exterior portions of the walls of the building.

Figure 2 is a horizontal section taken along the line 2—2 of Figure 1.

Figure 3 is a horizontal section similar to that shown in Figure 1 but disclosing a modified form of the building.

Figure 4 is a fragmentary vertical section of a wall of one of the buildings showing an opaque lower wall and a translucent upper wall.

Figure 5 is a front view in elevation of a modi-

fied form of the display apparatus in which an advertising sign is applied to the top of a building, and

Figure 6 is a horizontal section of the advertising sign shown in Figure 5.

Referring more particularly to Figures 1 and 2, 10 designates a building which has its lower half constructed of brick or concrete walls 11, while the upper portions 12 of the walls are formed of translucent materials such as glass, cloth or a plastic to provide screens so that stills or moving pictures projected onto said screens will be visible from the inside and outside of the building. The screens 12 are mounted preferably in

frames secured to the tops of the walls 11.

Mounted opposite each screen 12 is a post 15 which terminates at the upper end at a point substantially midway between the upper and lower edges of said screens. A projection apparatus 16 is mounted on the top of each post for projecting a still or the frames of a moving picture film onto the screens. The scenes depicted on all of the screens may be identical or they may be varied as desired. Since the screens are translucent, the scenes will be visible to persons inside and outside of the building. The projection apparatuses are controlled for simultaneous operation.

In Figure 3, a modified form of the building is shown only. The building 20 is in the shape of an octagon with seven sides thereof having the upper portion provided with translucent sections 21 which are above the furnishings and the heads of the patrons and upon which scenes are projected from individual projection machines 22 mounted on posts 23. A dance floor 24 is located at the center of the building and surrounded by a runway 25 for tables. A band stand 26 is adjacent a wall 27 of the building which does not carry a translucent screen 21. A railing 28 encloses the dance floor.

An auxiliary building 30 includes the wall 27. This building houses a kitchen, rest rooms and other rooms necessary for the comfort of the guests.

In Figures 1 to 3, inclusive, the machines will project stills or moving picture films onto the screens so that they will be visible to both persons on the inside and outside of the building. Thus, the illuminated screens will not only provide light for the interior of the building but entertainment for the guests and decorations for the upper portions of the inner walls of the building. The scenes or decorations may be changed at will to produce an unlimited variety of pic-

tures or designs. The changes may be made in accordance with the subject matter of musical compositions played by the orchestra to create a different atmosphere, such as an Hawaiian, a Chinese or a South American.

In Figures 5 and 6 is illustrated a modified form of an illuminating means. A building 35 which may be a restaurant or stand has an enclosed casing 36 housing lamps or projecting machines 37. The front of said casing is closed by a pair of inclined translucent walls 38 and 39 and a top. The walls are inclined toward each at an acute angle or at right angles and the outer ends are joined together. One of the devices 37 throws a light or projects an image which may be advertising matter, on the screen or translucent wall 38 while the wall 39 receives light rays from the other device. Constantly changing matter may be projected on the screens 38 and 39. The casing 36 is secured to the roof of the building 35 adjacent one wall so that the screens will extend over the building in a conspicuous manner for visibility at a distance.

It is to be borne in mind that the people in a room in the building as well as the furnishings do not at any time stand between the projector and the translucent walls thereof. Thus they do not interfere with the projected pictures on the translucent wall whether stills or motion pictures are employed. In practice, the entire walls will be translucent screens thus giving the illusion to the guests that they are surrounded by the scenery. The projections will not only include scenes but patterns and designs.

The building shown in Figure 3 is a one-story structure without a roof. It is the type commonly

seen in the United States and Canada. It is a simple structure, consisting of a single room, and is used for various purposes, such as a restaurant, a dance hall, a theater, a hall for public meetings, etc. The building is provided with a door 30 and a window 31. The door 30 is located on the side of the building, and the window 31 is located on the front of the building. The building is provided with a roof 32, which is supported by a series of columns 33. The roof 32 is provided with a series of skylights 34, which are located on the top of the roof 32. The skylights 34 are provided with translucent walls 35, which are inclined toward each other at an acute angle. The translucent walls 35 are provided with a series of windows 36, which are located on the side of the translucent walls 35. The windows 36 are provided with translucent curtains 37, which are provided with a series of patterns and designs.

The building is provided with a series of doors 38, which are located on the side of the building. The doors 38 are provided with translucent curtains 39, which are provided with a series of patterns and designs.

The building is provided with a series of windows 40, which are located on the front of the building. The windows 40 are provided with translucent curtains 41, which are provided with a series of patterns and designs.

The building is provided with a series of doors 42, which are located on the side of the building. The doors 42 are provided with translucent curtains 43, which are provided with a series of patterns and designs.

The building is provided with a series of windows 44, which are located on the front of the building. The windows 44 are provided with translucent curtains 45, which are provided with a series of patterns and designs.

The building is provided with a series of doors 46, which are located on the side of the building. The doors 46 are provided with translucent curtains 47, which are provided with a series of patterns and designs.

called a "beach club." The projection screens forming the walls of the building should be high enough to clear automobiles and are made of any well-known translucent material.

What I claim is:

A building including a guest entertainment room having a plurality of enclosing walls, each of said walls including a lower portion fabricated of opaque building material and the upper portions fabricated of translucent material, the latter named portion forming a projection screen, a picture projection machine located exteriorly of the building and in spaced relation with respect to each of the screens for projecting scenes and decorative matter on said screens, and means for supporting the projection machines in alignment with said screens, the screens being supported by the upper edges of the lower portions of the walls at a sufficient height above the guests and furnishings in said room to enable each screen to be clearly viewed without obstruction by the guests within said room.
